UNITED STATES PATENT OFFICE.

ABRAHAM M. DELLINGER, OF LANCASTER, PENNSYLVANIA.

SHEAF-ELEVATOR.

1,395,561.

Specification of Letters Patent.

Patented Nov. 1, 1921.

Application filed November 17, 1919. Serial No. 338,560.

To all whom it may concern:

Be it known that I, ABRAHAM M. DELLINGER, a citizen of the United States, residing at Lancaster, in the county of Lancaster and 5 State of Pennsylvania, have invented certain new and useful Improvements in Sheaf-Elevators, of which the following is a specification:

This invention relates to elevators for 10 raising, directing and depositing hay, grain, straw or other loose materials in sheaves or otherwise, such elevators comprising an endless carrier having a vertical part and an upwardly and outwardly inclined part in 15 continuation thereof.

It is often necessary in the operation of 20 these machines to swing the inclined discharging end laterally, so that it might be presented in a different direction and discharge at a different point. To properly 25 brace and support the carrier and its frame, the machine has hitherto been attached pivotally at two different points, the lower pivotal or swiveling attachment being a universal joint at the base of the frame and 30 connecting the driving gearing, whereas the upper pivot is at or near the point of junction of a transverse bar or stay with the upper part of some barn wall as other fixed supporting structure, over the top of which 35 the discharge normally takes place. Thus the entire machine must be moved around in a swiveling way to change the point of discharge, which is a cumbrous proceeding, liable 40 to cause injury. Furthermore, the two pivotal points as hitherto constructed are considerably out of line vertically, involving great strain on the carrier, the frame and other parts whenever this swiveling operation occurs.

To avoid these objections I locate the upper pivotal point on the frame of the elevator, and make the vertical part of said frame in two sections, the upper section being centrally pivoted at its lower end on the upper end of the lower section. As the two pivots are nearly in the same vertical line and the lower pivot is made slightly loose on its bearing to avoid all strain, the upper section 45 of the frame turns freely and is properly supported at these two points in doing so, leaving the lower part of the frame, with all its gearing and attachments, quite undisturbed.

My invention consists in the above described improved construction and in some additional details of construction and combination hereinafter particularly set forth.

In the accompanying drawings:

Figure 1 represents a side elevation of a 60 sheaf elevator embodying my invention attached to the frame of a barn partly sectioned, the nearer side board of the guide trough for the inclined upper extension of the carrier having been removed.

Fig. 2 represents a cross section on the line $x-x$ of Fig. 1 looking downward, the barn wall not being sectioned, and the gearing being shown in plan view.

Fig. 3 represents a front elevation of the 70 sheaf elevator at right angles to Fig. 1 looking from the right.

Fig. 4 represents an enlarged detail view in side elevation of the upper pivot and its means of attachment to the frame, the bar 75 which it enters being partly broken away.

Fig. 4^a represents a plan view of the same.

Fig. 5 represents an enlarged detail view in side elevation of the lower pivot and the bearing in which it turns, the latter being 80 shown of such size as to allow some play of said pivot and avoid binding and strain.

Fig. 5^a represents a vertical sectional view of the same.

A designates a wall of a barn to which, 85 near the bottom, a casing B is attached affording bearings for the driving gearing. As shown, this mechanism consists of a driving belt wheel C, a bevel wheel D turning therewith, an intermeshing bevel wheel E 90 and a sprocket wheel F connected to a sprocket wheel I at the lower end of the endless conveyer or carrier J by a short endless chain G held taut by an adjustable clamp H attached to the lower section of the frame. 95 We do not confine ourselves to this precise arrangement and combination of gearing, as the same may manifestly be considerably changed by substitution of well known equivalents. There is no universal joint or 100 other pivotal device between the belt wheel C and the other gearing or anywhere else in the driving mechanism. The carrier J travels over sprocket wheels j j' j^2 j^3 in a manner heretofore known as well as over its 105 lower sprocket wheel J', which last is on the same short transverse shaft K as the sprocket wheel I aforesaid. This endless carrier in

the usual way travels upward in a vertical flight, then upward and rearward by inclined flight to the point of discharge, then preferably abruptly downward and obliquely downward approximately paralleling its former flight to the sprocket wheel J' again. I do not now claim anything in this construction and arrangement of the endless conveyer.

- 10 The frame of the elevator necessarily corresponds in some degree to the form of the said conveyer. It comprises an inclined part or section 3 and a vertical part to which said inclined part is jointed. This vertical part 15 consists of a lower section 1 and an upper section 2. At its lower end the section 2 is provided with a sheathing or shield 3 of U shape extending under said frame, and a pivot pin 4 centrally arranged and extending 20 downward into a bearing socket 5 in the center of the crown of the lower frame section 1. The latter is of the shape of an elongated U inverted and narrowed at its upper end to form said crown.
- 25 Its lower ends are supported by bracket B and provide bearings for the shaft E' of bevel wheel E and sprocket wheel F. The above construction, combination and arrangement of frame sections 1 and 2 and 30 pivot pin 4 in central alinement with them permit section 2 to turn on section 1 without getting out of alinement therewith.

The upper pivot 6 is attached to the side of section 2 by a plate 7 bolted thereon, 35 see Figs. 1 and 4. Said pivot pin 6 is presented downward, entering a bearing socket 8 in the end of a bar M projecting horizontally from the barn wall toward the elevator. The two pivots 4 and 6 are nearly 40 in alinement and the slight discrepancy in this respect is allowed for by making the lower socket 5 somewhat larger than the pin 4, as shown in Fig. 5. Consequently there will be no injurious binding at these points. 45 The inclined uppermost part 3 of the frame and the corresponding part of the carrier may be directed at will to discharge over any desired point in a wide sweep without moving or disturbing the lowest section 1 50 of the frame or the gearing at its base at all.

The section 2 is preferably of T shape in cross section, presenting its broad face away from the barn and parallel to the wall 55 thereof. Said section is provided with pairs of convenient brace bars LN extending to the wall of the barn and to a bar P which extends horizontally from the upper part of said section 2, affording a bearing for the 60 shaft R of sprocket j^3 which is located in the bend of the carrier. From the ends of this shaft brace bars O extend up to inclined part 3 of the frame.

Said part 3 is provided with a broad 65 guide trough to prevent lateral scattering of

the material brought up by the carrier. Short converging bars t and u, Fig. 1, afford a pivot for a lever 9 which bears the lower sprocket wheel j^2 of the pair of terminal sprocket wheels. The end of this little 70 lever is jointed to an adjusting rod V which passes through a lug W attached to part 3 of the frame and is screw threaded to engage a nut X beyond said lug. By turning this nut to draw on said rod and said lever the 75 sprocket wheel j^2 is caused to bear against the inside of the downward flight of the carrier J and make its discharging end more truly vertical and also acts as a chain tightener.

Having thus described my invention, what I claim as new and desire to secure by Letters Patent is:

1. An elevator provided with a sectional frame, said frame having an upper vertical section which is pivoted at two points in different horizontal planes, and a lower section arranged to remain motionless relatively to said vertical section. 85

2. An elevator provided with a sectional frame, said frame having an upper vertical section, an endless carrier mounted on said frame, said frame having its upper vertical section pivoted at two points substantially in line vertically. 95

3. An elevator for sheaves of grain, having a frame consisting of an inclined upper section and a vertical part comprising a lower and an upper section, the latter section being pivoted at two points practically 100 in vertical alinement.

4. In an elevator the combination of an endless carrier with a frame for the same consisting of three connected sections, and a pivot supported by a fixed structure and connected to the upper portion of the middle section of the frame, for allowing horizontal turning of said middle section, the latter being connected to the lower section of the frame but free to turn horizontally thereon. 105

5. An elevator having an upright frame in three sections arranged end to end, the lowest section being stationary, the uppermost section being inclined and pivoted to the middle section and the middle section 115 being connected to the lowest section by a pivot which allows said middle section to turn horizontally and also being provided near its upper end with bracing means connected to it by a pivot which allows such horizontal motion. 120

6. In an elevator, the combination of an endless carrier with a frame for the same consisting of three connected sections, and a pivot supported by a fixed structure and connected to the upper portion of the middle section for allowing horizontal turning of said middle section, the latter being connected to the lower part of the frame by a vertically disposed loose pivot substantially 125 130

aligned with the first mentioned pivotal connection to permit free horizontal turning movement of the middle section relative to said lower section and slight compensating 5 sliding movement to allow for the slight relative displacement of the pivots.

In testimony whereof, I have signed my

name to this specification in the presence of two subscribing witnesses.
